UNITED STATES PATENT OFFICE

CLARA ZUCKERMANN, OF VIENNA, AUSTRIA

CLOTHES HANGER

Application filed January 21, 1929, Serial No. 333,912, and in Germany October 11, 1928.

The present invention comprises a clothes hanger which is formed or provided with means for attaching thereto a protecting cover for the clothes which are to be placed on 5 the hanger.

Conveniently and advantageously the device consists of a ring connected to the hook rod and preferably made in one piece therewith, and to which the covering is attached 10 by means, for example, of small slide rings or runners. For this purpose in the herein-after described example, the hook rod is bent in the middle, formed into a ring and closed on to the first bent portion in such a way that 15 it lies against it and, after a further bend, forms the continuation of the straight portion of the hook, the lower end of which carries the shoulder or cross-piece for carrying the clothes.

20 One form of carrying out the present invention is shown by way of example in the accompanying drawings, in which Fig. 1 represents a clothes hanger according to the present invention without a protection cover, 25 and Fig. 2 the same hanger with the protection cover applied thereto.

c designates the usual hook and *a* the shank or rod thereof which is screwed into or otherwise attached to the shoulder *b* of 30 the clothes hanger and is bent horizontally at *d* to form a horizontal portion *e*. The shank or rod is again bent at *f* and formed into a ring *g* which is closed at *f*₁. Here the hook rod or shank *a* is again bent horizontally 35 towards the centre of the ring, to form the portion *e*₁ which lies against the portion *e* and is again bent downwards at the centre of the ring at *d* in order to form a prolongation *d*₁ of the straight hook rod *a*. At its 40 lower end the portion *a*₁ may be fitted with an ordinary thread *h* by means of which it can be screwed into the shoulder or cross-piece *d*. On to the ring *g* are run small rings *i* to which can be secured the cover *k* which 45 serves the purpose of protecting the clothes (Fig. 2).

In the one-piece hook construction described and shewn it will be seen that the rings *i* can be run on to the ring *g* by passing them on to the ring *g* over the hook *c*, the por-

tion *a* and the portion *e*, the portions *e* and *e*₁ springing apart to allow of the small rings *i* being inserted and coming together again after the rings *i* have been inserted, just in the same way as a key-ring, so that the ring 55 *g* is always closed after the small rings *i* have been put on. After a sufficient number of small rings *i* have been run on to the hook ring *g*, the cloth cover is sewn on or otherwise attached to the small rings. 60

Having now particularly described and ascertained the nature of the said invention and in what manner the same is to be performed, I declare that what I claim is:

1. In a clothes hanger of the character described, a suspending hook having a bent portion, a yoke carried thereby, and a protecting cover comprising a ring formed integrally with said bent portion of said hook, said ring open at its meeting place with said bent portion to allow the threading of a plurality of rings upon said ring, and a curtain suspended therefrom. 65

2. A garment protector and hanger comprising a yoke, a suspension member for same, an intermediary substantially ring-shaped portion integrally formed with said member, said ring shaped portion being divided to allow a separation of its parts for permitting the threading of rings on said ring portion, 70 and a curtain suspended from said rings to envelop garments suspended from said yoke. 75

3. A clothes hanger having means for attaching a protecting cover for the clothes thereto in which the cover attaching means consists of a ring in connection with the hook component of the hanger, the ring being formed out of a bent portion of the hook rod the bent portions (*e*, *e*₁) between the ring (*g*) and the hook rod (*a*, *a*₁) lying against each other in such a way that they can spring apart when rings which serve the purpose of attaching the protecting cover to the hook ring (*g*) are being inserted and can come together again after the rings have been inserted. 80

In testimony whereof I affix my signature.

CLARA ZUCKERMANN.
